(57) **CLAIM**

The ornamental design for a gaming machine, as shown and described.

DESCRIPTION

FIG. 1 is a front isometric view of the gaming machine of the present invention;

FIG. 2 is a top plan view of the gaming machine illustrated in FIG. 1;

FIG. 3 is a front elevation view of the gaming machine illustrated in FIG. 1;

FIG. 4 is a first side view of the gaming machine illustrated in FIG. 1;

FIG. 5 is a second side view of the gaming machine illustrated in FIG. 1;

FIG. 6 is rear elevation view of the gaming machine illustrated in FIG. 1; and,

FIG. 7 is a bottom plan view of the gaming machine illustrated in FIG. 1.

The broken lines in the drawings are for the purpose of illustrating portions of the gaming machine which form no part of the claimed design.
